FLY CLOSURE

William R. Spearrin, Naugatuck, Conn., assignor
to Scovill Manufacturing Company, Waterbury,
Conn., a corporation of Connecticut

Application November 19, 1946, Serial No. 710,932

10 Claims. (Cl. 2—234)

1
This invention relates to trouser garments and particularly to a cut-on type of fly front construction for such garments and wherein separable snap fastener elements are employed and set along the full length of a fly front construction such as employed in various types of garments.

The principal object of this invention is to design a fly front construction to accommodate a series of separable snap fastener elements and particularly to redesign the cut-on fly front construction so as to make it more convenient for the wearer in the manipulation of the snap fastener elements for closing up a fly front. This is accomplished by initially cutting one side of a fly front construction with sufficient material to permit a double folding of the material, one fold of two-ply material consisting of a second fly strip to which fastener elements are attached, and this second fly strip folded back upon a portion of the garment considered the under-right fly strip proper and bar tacking it thereto at equal distances between the attached fastener elements, thus providing individual pockets as a part of the under-right fly and within which the thumb of the wearer's hand may be inserted in the act of snapping the elements together.

Another object in designing this cut-on type of fly front construction is to arrange the material such that in folding it over, the second fold will be positioned away from the extreme edge of the garment to preclude a building up of the garment material along that fly edge.

The invention will be better understood from the detailed description that follows when considered in conjunction with the accompanying drawing showing a certain preferred embodiment of my invention and wherein—

Fig. 1 is a front view of a fly construction such as might be employed in trouser garments and showing one part of the front fly construction in partially open position.

Fig. 2 is a development layout of the under-right fly portion of the garment showing the pattern as it would be before the folding operations.

Fig. 3 is a vertical sectional view taken along the line 3—3 of Fig. 1, but with the fly front construction in closed position.

Fig. 4 is a horizontal sectional view taken along the line 4—4 of Fig. 1, but showing the fastener elements in a position about ready to be snapped together.

Fig. 5 is a view similar to Fig. 4, but showing the garment as it would be with the snap fasteners snapped together, and

Fig. 6 is a diagrammatical perspective view showing how the upper end of the under-right fly portion of the garment appears when folded.

Referring now in detail to the drawing the 60 lining strip is attached to the outer edge of the

2
numeral 10 designates the right front portion of a trouser garment construction adjacent the fly front opening. The numeral 11 designates the left front portion of the garment construction adjacent the fly portion. The front portions 10 and 11 are brought together below the fly front opening by an infolded joining seam 12.

In using the terms "right" and "left" to designate certain parts of the garment, I choose to use 10 these terms in the specification as they are conventionally used in connection with the actual garment and not as to the position of the parts as they happen to appear in the patent drawing. It, therefore, should be understood that, 15 when I refer to the under-right fly part of the garment, it will appear at the left of the drawing and the upper left fly part will appear at the right of the drawing.

To provide a cut-on type of fly front construction the pattern followed is more or less in accordance with that shown in Fig. 2. Here specifically the right front portion of the garment 10 is extended beyond an imaginary line shown as a dash and double dot line 13 to a fold line indicated by a dot and dash line 14 referred to as the second fold line and which included material will hereinafter be considered the under-right fly strip 15 proper. The lower edge of this under-right fly strip 15 is cut on a bias and preferably in the form of an arc 16 that is substantially tangential to the second fold line 14. Extending from the second fold line 14 to another fold line 17, considered the first fold line, is another strip of included material 18, conveniently termed the mid section, the lower edge of which is likewise cut on an arc 19 comparable to the arc 16. Extending beyond the so called first fold line 17 is the remaining portion of the cut-on fly front material designated by the 20 numeral 20, and the lower edge of this fly front portion being likewise cut on an arc 21 somewhat comparable to the arc 19.

Below the under-right fly strip proper 15 the garment is extended as at 22 to provide a sufficient amount of material to the right front portion of the garment to have its end fold and stitched together with the adjacent folded edge of the left garment portion 11 as at the infolded seam 12 previously mentioned. The upper edge 25 of extended portion 22 is cut on a bias or an arc 22a having considerable clearance and in a diverging manner relative to the arcuate cut 16 immediately above.

As is the usual custom with all fly front constructions a facing or lining strip 23 is provided to lie back of the under-right fly strip 15. When the extended portion of the garment material for the cut-on fly construction is in its extended position as shown in Fig. 2, the outer edge of this 30 lining strip is attached to the outer edge of the

end material 20 by a line of stitching 24 extending even through the arcuate portion 21. The two portions 18 and 20 are next folded upon themselves along the first fold line 17 to provide a double-ply fly strip 25 conventionally termed the second fly strip. With the sections 18 and 20 thus folded, a series of fastener elements, preferably studs 26, are set along this strip in equally distanced positions. For the next operation the double-ply second fly strip 25 is folded over against the front of the under-right fly strip 15 along the second fold line 14. It is to be noted that the width of the garment fly portion 20 is somewhat wider than the adjacent mid portion 18. This difference in the width of the adjacent portions 18 and 20 is purposely designed so as to cause the second fold line 14 to be disposed somewhat back from the end or edge portion of the fly strip where the lining is attached thereto as best shown in Figs. 5 and 6. With the fastener elements 26 attached and the second fly strip 25 folded over upon the under-right fly strip 15, the former strip 25 is then secured to the under-right fly strip 15 at equally spaced intervals as by bar tackings 27, and thus provides a series of pockets 28 (see Fig. 4), the purpose of which will later appear. After the bar tacking operation the outer ends of the garment portion 20 and the lining 23 are folded back upon itself as shown in Figs. 4 and 6 with the lining disposed in back of the under-right fly strip 15. The inner end of this lining is folded back upon itself as at 29 and finally stitched to the garment proper as by a line of stitching 30, which line of stitching is more or less in alignment with the seam 12 previously mentioned and as seen in Fig. 1.

Considering now the upper left fly front construction the garment is designed to have a portion overlie the under-right fly strip, which portion is indicated by the numeral 31. To the underside of this garment portion 31 is secured a under fly strip 32. However, before this under fly strip 32 is secured in place in order to reinforce it sufficiently to take complemental fastener elements for the stud elements 26 on the second fly strip 25, a reinforcing strip 33 is stitched to the inner face of said fly strip 32 as by line stitching 34 along the opposite edges thereof, thus providing for a double ply section for the under-fly strip 32. Socket elements 35 complemental to the stud elements 26 and equally spaced are secured to the double ply portion of the under fly strip 32. The fly strip 32 with the reinforcing portion 33 stitched in place and the elements 35 attached thereto is next secured to the outer end of the garment fly portion 31 by a line of stitching 36, and the ends folded back to form an in-turned seam 37 in the manner as best shown in Fig. 4 with the under fly strip 32 caused to underlie the garment fly portion 31. The inner end of the under fly strip 32 is finally secured in place to the left front portion proper 11 as by a line of stitching 38.

To finish off the upper part of the garment the usual form of waist band may be secured thereto. As best shown in Fig. 3 the waist band attached to the right front portion 10 of the garment is of double material thickness 40 having its upper end infolded as at 41 and stitched together by a line of stitching 42 in the usual manner. The lower ends of the two ply material of this right waist band 40 are spread apart and each lower edge infolded upon itself as at 43, and compressed against the opposite sides of the garment part 10 and at the under-right fly section embracing 75

the under-right fly strip 15, the lining strip 16 and the double-fold second fly strip 25, and all folded parts stitched together as by a line of stitching 44. Adjacent the end of this right waist band 40 is secured a stud element 45 through both thicknesses of the waist band material and in vertical alignment with the stud elements 26, the element 45 being identical with elements 26.

The left waist band construction 46 is made and 10 attached in a similar manner to the right waist band 40, having at its upper edge formed with an infolded seam 47 and stitched at 48. The lower ends of the two ply material of the left band 46 are likewise spread and infolded as at 49 and stitched as at 50 to the left portion of the garment 11, and at the fly portion including the upper left garment portion 31, the under fly strip 32 and the reinforcing strip 33. After the left waist band 46 is secured in place a socket element 51 complemental to the stud element 45 is secured adjacent the end thereof in vertical alignment with the socket elements 35 previously referred to.

It is to be noted that all the studs 26 by the 25 manner in which they are attached to the double folded portion 25 are concealed and covered relative to the under side of the garment part 10, and it is only the attaching element of the stud 45 secured to the right waist band 40 that shows to 30 the under face of the garment. Similarly all the socket elements 35 carried by the upper left fly construction are concealed from the front portion of the garment except for the uppermost socket element 51 secured to the left waist band 35 46, and this will be covered by the belt normally worn with the trousers.

In the closing up of the fly front by reason of the pockets 28 that are provided in the under-right fly portion, it will be a relatively simple 40 matter for the wearer to slip one's thumb into the several pockets so as to support the underside of the stud members 26 while compressing the front of the upper-right fly portion 31 by the index finger for snapping the series of separable snap fastener elements together in the manner as clearly shown in Fig. 4. By this construction it eliminates the necessity of having to force one's thumb underneath the under-right fly portion as would be required if the fastener elements were attached directly to the fly strip 15.

It is, of course, obvious that minor changes in details of construction and arrangement of parts may be made without departing from the scope of the present invention as set forth in the appended claims.

I claim:

1. In a fly construction for a garment comprising right and left garment portions stitched together at an infolded seam below the fly construction, the right garment portion at its fly edge being extended to provide for a triple fold of material, one fold portion providing a two ply thickness for the second fly strip, a series of spaced fastener elements attached to said second fly strip, the latter being folded back upon the front portion of the garment or fly strip proper and bar tacked thereto at equally spaced positions between said elements to provide for a series of pockets within which the wearer can insert his thumb and support the underside of the element, an underlying fly strip stitched to the underside of the left garment portion, and elements complemental to the first named elements attached to said underlying fly strip and being concealed from the front of said garment.

2. In a fly construction for a garment comprising right and left garment portions stitched together at an infolded seam below the fly construction, the right garment portion at its fly edge being extended to provide for an integral under-right fly section and a double ply second fly strip folded inwardly from said under-right fly section and adapted to overlie the same, a series of spaced fastener elements attached to said second fly strip, the latter being bar tacked to the under-right fly section at equally spaced positions between said elements to provide for a series of pockets within which the wearer can insert his thumb to support the underside of the element, an underlying fly strip stitched to the underside of the left garment portion, and elements complementary to the first named elements attached to said underlying fly strip and being concealed from the front of said garment.

3. In a fly construction for a garment comprising right and left garment portions stitched together at an infolded seam below the fly construction, the right garment portion at its fly edge being extended to provide for an integral under-right fly section and a double ply second fly strip folded inwardly from said under-right fly section and adapted to overlie the same, a series of spaced fastener elements attached to said second fly strip, the latter being bar tacked to the under-right fly section at equally spaced positions between said elements to provide for a series of pockets within which the wearer can insert his thumb to support the underside of the element, the opposite or upper-left fly section formed as a part of the left portion of the garment and adapted to normally overlie the under-right fly section, and a series of equally spaced fastener elements secured thereto which latter elements are complementary to the elements secured to the second fly strip.

4. In a fly construction for a garment comprising right and left garment portions stitched together at an infolded seam below the fly construction, the right garment portion at its fly edge being extended to provide for an integral under-right fly section and a double ply second fly strip folded inwardly from said under-right fly section and adapted to overlie the same, a series of spaced fastener elements attached to said second fly strip, the latter being bar tacked to the under-right fly section at equally spaced positions between said elements to provide for a series of pockets within which the wearer can insert his thumb to support the underside of the element, a lining strip having one end stitched to the extreme end of the double folded second fly strip and the opposite end stitched on a line about where the under-right fly section joins the right garment portion, the opposite or upper-left fly part constructed with an underlying fly strip stitched there in place, and elements complementary to the first named elements attached to the underlying fly strip and being concealed from the front of the garment.

5. In a fly construction for a garment comprising right and left garment portions stitched together at an infolded seam below the fly construction, the right garment portion at its fly edge being extended to provide for an integral under-right fly section terminated by a fold line, and another section adapted to be folded upon itself to provide a double ply second fly strip, a series of spaced fastener elements secured to said second fly strip, the latter adapted to be folded inwardly of the fold line terminating the under-

right fly section and over the same and being bar tacked thereto at equally spaced positions between said elements to provide for a series of individual pockets within which the wearer can insert his thumb to support the underside of the element from the front part of the garment, the outer folded portion of said second fly strip being of greater width than the adjacent innermost section so as to extend the outermost folded portion beyond the fold line of the under-right fly section and innermost section, a lining strip stitched to the edge of the outer folded portion and both parts folded back upon themselves with the lining strip underlying the under-right fly section and stitched thereto substantially on a line when the under-right fly section joins the garment proper, and an upper-left fly portion adapted to overlie the under-right fly section and having fastener elements secured thereto which are complementary to the elements secured to said second fly strip.

6. In a fly construction for a garment as defined by claim 5 wherein the lower edges of the three distinct sections of the extended right garment portion are angularly cut in such a manner as to be coincident with each other when the three distinct sections are folded back upon each other.

7. In a fly construction for a garment, comprising right and left garment portions stitched together at an infolded seam below the fly construction, the right garment portion at its fly edge being extended to provide for an integral under-right fly section terminated by a fold line, and another section adapted to be folded upon itself to provide a double ply second fly strip, a series of spaced fastener elements secured to said second fly strip, the latter adapted to be folded inwardly of the fold line terminating the under-right fly section and over the same and being bar tacked thereto at equally spaced positions between said elements to provide for a series of individual pockets within which the wearer can insert his thumb to support the underside of the element from the front part of the garment, the outer folded portion of said second fly strip being of greater width than the adjacent innermost section so as to extend the outermost folded portion beyond the fold line of the under-right fly section and innermost section, a lining strip stitched to edges of the outer folded portion and both parts folded back upon themselves with the lining strip underlying the under-right fly section and the innermost end of said lining strip likewise being folded back upon itself and stitched to the under-right fly section substantially in line when the latter joins the garment proper, and an upper-left fly portion adapted to overlie the under-right fly section and having fastener elements secured thereto which are complementary to the elements secured to said second fly strip.

8. A fly construction for a garment as defined by claim 7 wherein the upper-left fly portion is constructed with an underlying reinforced fly strip to which the complementary fastener elements are attached and are concealed from the front portion of the garment.

9. In a fly construction for a garment comprising right and left garment portions having upper and lower overlapping fly edges, the lower fly edge being extended to provide for a triple fold of material, one fold portion providing a two ply thickness for the second fly strip, a series of spaced fastener elements attached to said second fly strip, the latter being folded back upon the

front portion of the garment or fly strip proper and bar tacked thereto at equally spaced positions between said elements to provide for a series of pockets within which the wearer can insert one's thumb and support the underside of the upper overlapping fly edge, and elements complemented to the first named elements attached to said underlying fly strip and being concealed from the front of the garment.

10. In a fly construction for a garment comprising right and left garment portions having upper and lower fly edges adapted to overlap each other, the garment portion having the lower fly edge being extended to provide for an integral underneath fly section and a double ply second 15

fly strip folded inwardly from the under fly strip and adapted to overlie the same, a series of spaced fastener elements attached to said second fly strip, the latter being bar tacked to the underneath fly section at equally spaced positions between said elements to provide for a series of pockets within which the wearer can insert one's thumb to support the underside of the element, the opposite or upper fly section formed as a part 10 of the garment and adapted to normally overlie the under fly section, and a series of equally spaced fastener elements secured thereto, which latter elements are complemented to the elements secured to the second fly strip.

WILLIAM R. SPEARRIN.
